UNITED STATES PATENT OFFICE.

JAMES B. CLARKE, OF WOODLAWN, PENNSYLVANIA.

METHOD OF AND MEANS FOR HEATING METAL ARTICLES.

1,300,347.

Specification of Letters Patent. Patented Apr. 15, 1919.

Application filed February 2, 1918 Serial No. 215,168.

To all whom it may concern:

Be it known that I, JAMES B. CLARKE, residing at Woodlawn, in the county of Beaver and State of Pennsylvania, a citizen 5 of the United States, have invented or discovered certain new and useful Improvements in Methods of and Means for Heating Metal Articles, of which improvements the following is a specification.

10 My invention relates to methods of and means for heating metal billets, bars or blanks prior to rolling or otherwise treating them in a heated condition.

The heating of such articles is frequently 15 effected by continuous heating furnaces which comprise elongate heating chambers provided at one end with a charging and at the other end with a discharging opening, the billets being caused to enter the charging opening and to move slowly through the heating chamber until they reach the discharge opening, through which they are removed and passed to the rolls.

For heating billets in such furnaces the 25 present practice is to introduce air and a combustible gas into the discharge end of the furnace and to effect combustion at such end, the gases resulting from the combustion being conducted rearwardly through 30 the heating chamber toward the charging end of the furnace, and from thence to a stack or some other means of disposal. Thus a high heating zone is maintained at the discharge end of the furnace, and the 35 remainder of the furnace is heated only by the products of combustion, with the result that the billets are mainly heated at the discharge end, considerable time being required for doing so.

40 In the practical operation of continuous heating furnaces of the character described, it has been found to be impossible to effect complete combustion of the gases in the high heating zone at the discharge end of the 45 furnace; and, my invention proceeds upon my discovery that, by introducing air into the heating chamber at a point intermediate the charging and discharging ends of the furnace, complete combustion of the gases 50 may be effected, and that in consequence thereof the portion of the furnace to the rear of the heating zone may be maintained at a much higher temperature than heretofore possible with the result that the output 55 of the furnace may be materially increased,

substantially less time being required to effect the desired heating of the billets.

While air may be variously introduced into the heating chamber for effecting the further combustion of the gases in the manner stated, it is preferably introduced through the top of such chamber in downwardly and rearwardly projecting streams substantially midway between the charging and discharging ends of the furnace.

In the accompanying sheet of drawings which form part of my specification, I have illustrated my invention in its adaptability to two specific types of continuous heating furnaces.

Figure 1 is a plan view of one type of furnace; Fig. 2 a vertical sectional view taken on the line II—II, Fig. 1; Fig. 3 a side view of the furnace of Fig. 1; Fig. 4 a combined plan and horizontal sectional view 70 of a second type of furnace, the plane of view of the half of the furnace shown in section being indicated by the line IV—IV, Fig. 5; and Fig. 5 a vertical sectional view 75 of the furnace of Fig. 4; the plane of view 80 being indicated by the line V—V, Fig. 4.

Having reference first to the furnace of Figs. 1, 2 and 3, the heating chamber 1 is formed by and between a downwardly inclined floor 2, an arched top 3, end walls 4 and 5 and side walls 6 and 7. Billets to be heated are, by means of a suitable ram 8, pushed into the furnace through a charging opening 9 formed in the rear end wall 5; are then caused to gradually slide down the inclined floor 2; and, when properly heated, are removed from the furnace through a discharge opening 10 formed in the side walls 7 at the front or discharging end of the furnace. Air and gas under suitable pressure 90 are introduced through a passageway 11 into the heating chamber at the discharge end of the furnace, combustion taking place immediately upon the entrance of such gases, and the heated gases resulting from 95 such combustion being conducted backwardly through the heating chamber to a passageway 12 at the charging end of the furnace. Through this passageway the gases are carried downwardly to a stack or 100 other means of disposal not shown herein.

For introducing air into the heating chamber for the purpose stated above, I preferably provide the top 3 of the heating chamber with a plurality of rows of air 110

conduits 13, which incline downwardly and rearwardly so that the streams of air are projected into the heating chamber in the same general direction as the rearward flow 5 of gases through it. It will be observed that the rows of conduits extend transversely of the heating chamber from one side to the other. While any desired number of rows of conduits may be provided 10 (in some instances one may be sufficient), three rows are shown herein. For supplying air to these conduits, they are connected to headers 14 and 15, which in turn are connected to a conduit 16 leading to a 15 suitable fan or blower 17 for generating the proper air pressure. The headers 14 and 15 and the conduit 16 lying immediately above the top 3 of the heating chamber, the air entering such chamber will become preliminarily heated. In addition to the transverse 20 rows of air conduits, several conduits 18 may extend through the side walls 6 and 7 of the heating chamber.

The essential difference between the furnace of Figs. 1, 2 and 3 and that of Figs. 4 and 5 is that in the latter the billets to be heated are supported on a skeleton floor or skids 19, and combustion is maintained below as well as above such support. Below 25 the support 19 a mixture of air and combustible gases enter the heating chamber through a passageway 20, while above such support such gases enter through a passageway 21. The gases resulting from combustion 30 both above and below the support are conducted rearwardly toward the charging end of the furnace and flow downwardly through a passageway 22. The furnace of Figs. 4 and 5 also differs from that of Figs. 35 1, 2 and 3 in that the discharge opening 23 is through the end wall 24 of the heating chamber.

The conduits for supplying air to the heating chamber at a point intermediate of the 40 charging and discharging ends thereof and above the support 19 are arranged substantially the same as those of the furnace of Figs. 1, 2 and 3, and need not be further described. Below the support 19 and projecting 45 upwardly and rearwardly, there are provided three rows of air conduits 25 each connected to a supply header 26, which in turn are connected to the conduit 27 leading to a blower or fan 28.

50 In heating billets according to my invention, sufficient air is supplied to the heating chamber of the furnace, at a position or positions to the rear of the normal high heating zone, to effect further and complete combustion of the gases entering the discharge end of the furnace. In actual operation it has been found that the temperature of the rear 55 part of the heating chamber may be mate-

rially raised by the admission of air in the manner described, with the result that the 65 billets or other articles to be heated reach the high heating zone of the chamber at a higher temperature than has been heretofore possible. Accordingly, the time required to heat a billet is substantially reduced and the 70 output of the furnace proportionately increased. Also it becomes unnecessary to maintain the high heating zone at the high 75 temperature which has heretofore been required, and as a consequence thereof the furnace lining will deteriorate or burn out less rapidly than it usually does. It will be observed of my invention that the increased output of the furnace is effected without increasing the supply of fuel, the resulting 80 economy being obvious.

According to the patent statutes, I have described the principle and mode of operation of my invention, together with the improvements in furnace construction which I 85 now consider to represent the best embodiment thereof. However, I desire to have it understood that, within the scope of the appended claims, my invention may be practised otherwise than as herein specifically 90 described and shown.

I claim as my invention:

1. A step in the fabrication of metal articles—as, for example, the rolling of pipe-skelp—the method herein described of heating a body of metal preparatory to shaping, such method consisting in causing the body to advance through a flame moving in opposite direction and nourished intermediate its length by fresh supplies of oxygen. 100

2. The method herein described of reheating a steel billet which consists in causing the billet to traverse a flame nourished intermediate its length by fresh supplies of oxygen in a direction opposite to that in which 105 the flame advances.

3. In a continuous heating furnace, the combination of a heating chamber having a charging opening at one end and a discharging opening at the other end, means for introducing air and a combustible gas into the discharging end of said chamber, means for removing the products of combustion from the chamber at the charging end thereof, a plurality of rows of conduits disposed transversely of the chamber and projecting downwardly and rearwardly through the roof thereof, and means for projecting air through said conduits. 110

In testimony whereof I have hereunto set 120 my hand.

JAMES B. CLARKE.
